UNITED STATES PATENT OFFICE.

KARL BAUMANN, OF URMSTON, ENGLAND, ASSIGNOR TO THE BRITISH WESTINGHOUSE ELECTRIC AND MANUFACTURING COMPANY LIMITED, A COMPANY OF GREAT BRITAIN.

AXIAL-FLOW STEAM-TURBINE.

1,386,983.

Specification of Letters Patent. Patented Aug. 9, 1921.

Application filed July 15, 1919. Serial No. 310,995.

To all whom it may concern:

Be it known that I, KARL BAUMANN, a citizen of the Confederation of Switzerland, and a resident of Urmston, in the county 5 of Lancaster, England, have invented a new and useful Improvement in Axial-Flow Steam-Turbines, of which the following is a specification.

This invention relates to axial flow steam 10 turbines in which the steam flowing through the low pressure portion is divided and flows in parallel through separate sections of blading each comprising one or more rows of stationary and moving blades to the 15 exhaust, and has for its object to provide an improved construction of turbine of this kind such that the divided portions of steam passing through said separate sections of blading flow in substantially the same axial 20 direction to the exhaust.

According to the invention one portion of the steam leaving the moving blades of an intermediate stage of the turbine flows through a section of blading comprising one 25 or more rows of stationary and moving blades and thence to the exhaust, while another portion flows through passages contrived in the disk, shaft or drum on which the rows of moving blades of the above mentioned section of blading are mounted, and thence through one or more further sections 30 of blading each comprising one or more rows of stationary and moving blades to the exhaust, said further section or sections of 35 blading being located farther along the shaft or drum of the turbine in the direction of steam flow than said first mentioned section.

In the accompanying drawings Figure 1 40 is a central, vertical, longitudinal section of the low pressure portion of a steam turbine constructed in accordance with this invention, Fig. 2 being a cross-sectional view on the line II—II of Fig. 1. Fig. 3 is a view 45 similar to Fig. 1 and Fig. 4 a cross-sectional view on the line IV—IV of Fig. 3 illustrating a modified construction. Fig. 5 is also a view similar to Fig. 1 and Fig. 6 a cross-sectional view on the line VI—VI of Fig. 50 5 showing another constructional modification. Like reference numerals are utilized throughout the several figures to indicate similar parts.

Referring first to Figs. 1 and 2, the turbine cylinder is indicated at 7 and the turbine shaft at 8, the exhaust casing at 9 and the exhaust outlet from the turbine at 10. The steam leaving the moving blades 11 of an intermediate stage is divided by a circumferential wall 12 formed in a diaphragm 13 secured in position in the turbine cylinder 7, into two annular portions an inner and an outer portion. The outer portion of steam flows through the diaphragm 13 outside the circumferential wall 12, through a section of blading comprising alternating rows of stationary and moving blades indicated respectively at 14, 15, 16, 17 and 18, and thence to the exhaust. The moving blades 14, 16 and 18 are mounted in a ring 19 shrunk on to the ends of a plurality of arms 20, 20 extending radially from the shaft 8. The spaces inclosed between the arms 20, 20 and the ring 19 shrunk on to their ends form a series of passages 21, 21 through which the inner portion of steam flowing through the diaphragm 13 within the circumferential wall 12 passes to another section of blading located farther along the shaft comprising rows of stationary and moving blades respectively indicated at 22, 23, 24, 25, 26 and 27 and thence to the exhaust. The stationary blades 22, 24 and 26 of this section of blading are mounted in a funnel-shaped diaphragm 28 secured in 85 position from longitudinal ribs 29 formed in the exhaust casing of the turbine. Said funnel-shaped diaphragm 28 extends into close proximity with the ring 19, and forms a guide for the steam leaving the row of 90 moving blades 18 and flowing into the exhaust and also a passage for the steam leaving the passages 21, 21 and flowing to the section of blading 22, 23, etc. The rows of 95 moving blades 23, 25 and 27 are mounted in the periphery of a disk or blade holder 30 shrunk on the shaft 8.

As illustrated in Fig. 1 the stationary 100 guide blades for the outer portion of steam between the rows of moving blades 11 and 14 are formed in the diaphragm 13 and although this is a convenient construction to adopt the diaphragm 13 may be so constructed as merely to support the circumferential wall 12 in position, a row of stationary guide blades being in such a case mount-

ed in the turbine cylinder in front of the moving blades 14 similarly to the rows of stationary guide blades 15 and 17.

The diaphragm 13 is preferably provided with an inner circumferential wall 31 to guide the inner annular portion of steam leaving the row of moving blades 11 toward the passages 21. The vanes, webs, or the like 31^a which serve to support the circumferential wall 31 from the wall 12 may with advantage be so formed as to deflect the inner annular portion of steam leaving the row of moving blades 11 so that it will enter the passages 21 with a minimum of 15 shock.

It will be observed that with the construction described above and illustrated in Figs. 1 and 2, both portions into which the steam leaving the row of moving blades 11 is divided flow in parallel in the same axial direction through the sections of blading 14 to 18 and 22 to 27, respectively, before reaching the exhaust.

The construction illustrated in Figs. 3 and 25 4 is, in many respects, similar to that described above with reference to Figs. 1 and 2. In this form of the invention however, the passages 21 for the inner annular portion of steam are milled out of the solid 30 shaft or rotor 8 as indicated and are extended in axial length so that at their ends they approach those portions of the shaft on which the rows of moving blades 11 and 23 are mounted. With this form the inner 35 circumferential guide wall 31 shown in Fig. 1 is omitted, the longitudinally curved shape of the base of the recesses forming the passages 21 as shown in Fig. 3, in conjunction with the circumferential wall 12 serving to 40 guide the inner annular portion of steam leaving the row of moving blades 11 into the passages below the ring 19. The construction illustrated in Figs. 3 and 4 enables 45 the turbine to be built with a more rigid shaft but otherwise the construction is very similar to that shown in Figs. 1 and 2. In either form the passages 21 may run parallel with the turbine axis or take a spiral or helical direction with reference thereto.

50 Figs. 5 and 6 illustrate the invention applied to a turbine in which the rows of moving blades are mounted on a hollow drum 32. The drum is provided with a plurality of slots or openings 33 through which the inner annular portion of steam leaving the row of moving blades 11 enters the interior of the drum 32. Two series of circumferentially arranged apertures 34, 35, respectively permit the steam which has entered 55 the drum to pass out again and flow through two further sections of stationary and moving blades, respectively indicated at 22, 23, 24, 25, 26, 27, and 22^a, 23^a, 24^a, 25^a, 26^a, 27^a.

With the construction illustrated in Figs. 60 5 and 6 it will be seen that the steam leav-

ing the row of moving blades 11 is subdivided into portions which flow in parallel and in the same axial direction to the exhaust through three independent sections of blading located at different points along the 70 shaft in the direction of the flow of steam through the turbine.

It is to be understood that the invention is not limited to the constructional forms herein described and illustrated which have 75 been given by way of example only as various changes and modifications may be made therein without departing from the spirit and scope of the invention.

I claim as my invention:

1. A steam turbine of the axial flow type in which the steam leaving the moving blades of an intermediate stage is divided, one portion thereof flowing through a section of blading comprising one or more rows 85 of stationary and moving blades and thence to the exhaust and another portion flowing through passages contrived in the rotor on which the rows of moving blades of the aforesaid section of blading are mounted 90 and thence through one or more further sections of blading each comprising one or more rows of stationary and moving blades to the exhaust, said further section or sections of blading being located farther along the rotor 95 in the direction of the flow of steam through the turbine than said first mentioned section of blading so that the several portions of steam leaving said intermediate stage will flow in parallel in the same axial direction 100 through all of said sections of blading.

2. In a steam turbine of the axial flow type having a casing on which stationary blades are mounted and a rotary drum on which moving blades are mounted and in 105 which the steam flows in the same axial direction through all sections of blading, means for dividing the steam leaving the moving blades of an intermediate section, means for passing one portion of the steam 110 through a low pressure section comprising one or more rows of stationary and moving blades and thence to exhaust, and means for passing another portion of the steam through the rotary drum to a succeeding low 115 pressure section comprising one or more rows of stationary and moving blades and thence to exhaust.

3. In an axial flow turbine, the combination with two low pressure sections through 120 which steam passes in parallel in the same axial direction, having a casing on which are mounted stationary blades and a rotor on which are mounted the moving blades of the sections, of means for passing steam through 125 the rotor to one of said low pressure sections.

4. In an axial flow turbine, the combination with two low pressure sections through which steam passes in parallel in the same axial direction, a casing on which are mount- 130

ed stationary blades and a rotor on which are mounted the moving blades of the sections, of means for directing the flow of steam through the rotor past one section and 5 to the other section.

5. In combination with an axial flow turbine comprising two low pressure sections through which steam flows in parallel in the same axial direction, a casing on which the 10 stationary blades and a rotor on which the moving blades of the sections are mounted, means for passing steam directly to the section located first in the direction of travel of the steam and means for passing steam 15 through the rotor to the other section.

6. In a turbine, the combination of a casing, a rotor, a section including blading carried by the casing and rotor, a plurality of successive low-pressure sections each including similarly arranged blading carried by 20 the casing and rotor and receiving steam discharged from the first-named section and discharging it in the same general axial direction, and means in the rotor for by-pass-

ing a portion of the steam discharged from the first-named section around the first low-pressure section and for supplying said steam to the other section or sections.

7. In a turbine, the combination of a casing, a rotor, a section carried by the casing and rotor, a plurality of successively arranged low-pressure sections carried by the casing and rotor, means carried by the casing for dividing the steam discharged from the first-named section into inner and outer 30 portions and discharging the outer portion into the first low-pressure section, means in the rotor for by-passing the inner portion around the first low-pressure section and supplying such portion to the other section 35 or sections, and guide means between the low-pressure sections to guide the exhaust of a low-pressure section around a succeeding low-pressure section and to guide said by-passed steam to the latter. 40

In testimony whereof I have hereunto subscribed my name this tenth day of June, 1919.

KARL BAUMANN.
